[57] **CLAIM**

The ornamental design for a bug and gravel shield for over the road trucks, as shown and described.

DESCRIPTION

FIG. 1 is a perspective view of a bug and gravel shield for over the road trucks showing my new design in position of use, it being understood that the fragmentary broken line depiction of a portion of a truck hood is for illustrative purposes only and forms no part of the claimed design;

FIG. 2 is a rear elevation view thereof;

FIG. 3 is a top plan view thereof;

FIG. 4 is a front elevation view thereof; and,

FIG. 5 is an end elevation view thereof, it being understood that the opposite end is a mirror image of that shown.
